UNITED STATES PATENT OFFICE.

JOSEPH R. DOOLEY, OF MOBILE, ALABAMA, ASSIGNOR OF ONE-HALF TO CORNELIUS W. VINK, OF MOBILE, ALABAMA.

RAILWAY-SWITCH LOCK.

Application filed October 11, 1923. Serial No. 667,882.

To all whom it may concern:

Be it known that I, JOSEPH R. DOOLEY, a citizen of the United States, residing at Mobile, in the county of Mobile and State of Alabama, have invented certain new and useful Improvements in Railway-Switch Locks, of which the following is a specification.

This invention relates to certain new and useful improvements in railway switch locks, and it has for its objects among others to provide a simple and reliable locking means for a railway switch that will lock the switch in a predetermined position, so as to eliminate all possibility of the train splitting the switch.

The present invention has for a further object to provide a simple, efficient and easily operated mechanism that can be applied to the shifting mechanism as at present used by all railroads without material change therein. The present invention comprises few parts and those readily assembled and not liable to get out of order or to be damaged in any way in use.

Other objects and advantages of the invention will hereinafter appear, and the novel features thereof will be specifically defined by the appended claims.

The invention, in its preferred form, is clearly illustrated in the accompanying drawings, which, with the numerals of reference marked thereon, form a part of this specification, and in which—

Figure 1 is a top plan showing the application of my present invention.

Figure 2 is a vertical cross section, as on the line 2—2 of Figure 1, looking in the direction of the arrows.

Figure 3 is a bottom plan of parts as shown in Figure 1.

Figure 4 is a vertical cross section as on the line 4—4 of Figure 1, looking in the direction of the arrows.

Figure 5 is an enlarged perspective detail, with the rail in vertical section and a portion broken away.

Figure 6 is a view of the yoke bar.

Figure 7 shows in perspective the rocker member and the parts associated therewith.

Like numerals of reference indicate like parts throughout the several views.

Referring to the drawings—

1 designates the ties, 2 the rails and 3 the switch, of usual construction. 55

The switch rails 3 are connected at a distance from their points by a transverse bar 4, the ends of which are pivotally connected as at 5 with the brackets, lugs or the like 6 which are secured to the adjacent faces of 60 the said switch rails in any suitable manner.

The switch rails are joined adjacent their points by the transverse bar 7 which constitutes the shifting bar, but this bar is not 65 rigidly connected to the switch rails but is provided near each end with an elongated slot 8, in which slots work the bolts or the like 9 which are carried by and project downward from the brackets or lugs or the 70 like 10 secured to the adjacent faces of the switch rails as seen best in Figure 4. This shifting bar 7 is mounted to slide within predetermined limits and one end is ex- 75

tended as seen at 11 and is pivotally connected at one end as at 12 with one end of the arm 13, the other end of which is connected with the pivot of the throw arm 14 the pivot 15 of which is supported in the bearing 16 on the tie or other support 17, all 80 as clearly seen in Figure 1. It will be seen that this connection between the switch rails and the bar 7 is such that the said shifting bar moves some little distance before the rocking member, soon to be described, begins to move.

18 is a yoke bar, preferably of steel, having its ends turned up as seen at 19, each of the said turned-up portions being peculiarly shaped, as seen, for instance, in Figure 5, 90 having a notch or the like 20 to engage the base 21 of the rail 2, and a second notch or recess 22 for cooperation with a wedge member 23 which is designed for cooperation with an oppositely disposed wedge member 24 which is adapted to bear against the web 25 of the rail 2 as seen in Figure 5. These two wedge members are constructed to be moved relatively to each other by means of a screw 26 and a nut 26^a thereon, as will be 100 readily understood from Figure 5. By this means is not only the yoke bar held securely in place, but the said means provides for adjustment so as to keep the pivot of the

rocking member, soon to be described, centrally between the rails and hold the rails to proper gauge. This also serves to prevent spreading of the rails at this point and aids all the parts in withstanding the strain incident to the operation of the switch rails.

At the centre of its length the yoke bar is provided, either integral, or made separate and affixed thereto in any suitable way 10 with a member 27 which is in the form of an inverted box-like compartment, see Figure 1, which carries the pivot 28 for the rocking member 29 to the free ends of the two arms 30 and 31 of which are pivotally connected 15 as at 32 the locking bars 33 and 34 as seen clearly in Figure 4. The free end of each locking bar is turned upward as seen in Figures 2 and 4 at 35, and at the angle each is provided with an elongated slot 36, through 20 each of which slots extends a horizontal bolt or the like 37 carried by the yoke bar 18. The upper ends of these upward extensions 38 are formed to engage the webs of the switch rails as seen in Figure 2.

25 Secured to the under side of the shifting bar 7 is a bracket 39 which depends therefrom, being provided with an elongated vertical slot 40, the bracket being flanged as at 41 and the securing bolts passing through 30 the top flange as seen clearly in Figure 3. The rocking member is provided with an open-ended slot 42 in which is received the block 43, 44 being a bolt which passes through the slot 40 in the bracket 39 and 35 through the slot 42, and through the said block and receiving the nuts 45 on opposite sides of the bracket 39.

The block 43 is provided with the hole 46 for the reception of the bolt 44, and opposite sides of this block are formed with the vertical channels 47 and 48, as seen in Figure 7, between the flanges 49 of which are received the lugs 50 which depend from the rocker member 29 upon opposite sides of the slot 42 therein, all as will be clearly understood from Figure 7.

50 By moving the bolt 44 upward in the elongated slot 40 in the bracket 39 the movement of the locking bar is shortened, and by 55 moving the said bolt toward the bottom end of the said elongated slot the movement of the locking bar is increased, thereby adding to its locking ability.

As seen best in Figure 6 the member 27 on the yoke bar 18 is provided with the depending lug 18^a having the hole 18^b for the reception of the pivot 28. The opposite edges 51 and 52 of the member 27 form stops for cooperation with the adjacent ends 53 and 54 of the members 33 and 34 as seen clearly in Figure 1.

The various parts above described may be made of any material suited to the purpose, and it will be evident that the proportions and relative arrangement of parts may be

varied within certain limits without departing from the spirit of the invention or sacrificing any of its advantages.

The locking device may be used upon either side of the shifting bar without any 70 change in any of the parts or their relative arrangement.

The operation will be readily understood from the foregoing description when taken in connection with the annexed drawings. 75 Briefly stated, it is as follows;—with the parts as shown in Figure 2 the left hand switch rail is thrown hard against the adjacent rail 2, the locking bar 33 is straight and horizontal and its portion 38 is forced hard against the switch rail 3, the other locking bar 34 being downwardly inclined, its face 54 having been moved out of contact with the shoulder or edge 52 of the member 18 and the upstanding end 38 of the right hand end of the said locking bar 34 out of contact with the adjacent switch rail 3.

When the lever 14 is moved into the opposite position the locking bar 33 is moved by reason of the rocking of the member 29 so 90 that the parts will be placed in the reverse position, the locking bar 34 being placed horizontally and the locking bar 33 caused to assume the downwardly inclined position, with the result that the opposite switch rail 95 is forced against the adjacent rail 2 and locked in such position.

Adjustment of the bolt 44 up or down as above described provides for the necessary adjustment of the throw of the locking bars. 100 The provision of the elongated slots 8 in the member 7 in which the bolts 9 play permits of the differential movement required to allow the shifting bar to move the requisite distance before movement is imparted 105 to the rocking member 29.

What is claimed as new is;—

1. In a railway switch lock, means for preventing spreading of the rails, and switch locking means pivotally supported therefrom. 110

2. In a railway switch lock, means for preventing spreading of the rails, and switch locking means pivotally rockingly supported thereby. 115

3. In a railway switch lock, means having portions to engage the outer faces of the rails for preventing spreading of the rails, and locking members supported by and co-operating with said means. 120

4. In a railway switch lock, means having portions to engage the outer faces of the rails for preventing spreading of the rails, and pivotally mounted locking members supported from and cooperating with said means. 125

5. In a railway switch lock, means engaging the outer faces of the rails to prevent spreading, a pivotally mounted rocker member, and oppositely disposed locking 130

bars pivotally mounted on said rocker member, and having limited loose connections with said means.

6. In a railway switch lock, a rocker member, oppositely disposed locking bars pivotally connected with opposite ends of said member, and rail-engaging means at the ends of said bars.

7. In a railway switch lock, a rocker member, locking bars pivotally connected therewith, and a shifting bar having connection with said bars.

8. In a railway switch lock, a rocker member, locking bars pivotally connected with opposite ends thereof, and a shifting bar having limited loose connection with said locking bars.

9. In a railway switch lock, a rocker member, a yoke bar on which the same is pivoted, locking bars pivoted to opposite ends of the rocker member, a shifting bar having loose connection with said locking bars, and means for varying the throw of said locking bars.

25 10. In a railway switch lock, a yoke bar having means for pivotally supporting a rocker member and means at the ends for grasping rails, and switch-rail moving and locking means rockingly mounted on said yoke bar.

30 11. In a railway switch lock, a yoke bar, having its ends to engage the rails, and wedge means for cooperation with said yoke bar and with the rails, and switch-rail mov-

ing and locking means rockingly mounted 35 on said yoke bar.

12. In a railway switch lock, a yoke bar, a rocker member pivoted thereon, locking bars connected with the rocker member, and means cooperating with the rocker member 40 for varying the throw of the locking bars.

13. In a railway switch lock, a yoke bar, a rocker member pivotally suspended therefrom, rocker engaging means for limiting the movement thereof, and locking bars 45 movable with the rocker member.

14. In a railway switch lock, a yoke bar, a rocker member on the same, a shifting bar having pivotal connection with the rocker member, means for actuating the 50 shifting bar, and switch rail locking means carried by the rocker member.

15. In a railway switch lock, a rocker member having a vertical slot, a bracket having a vertical slot, a block received in the 55 slot of the rocker member, and means engageable in said slots for pivotally supporting switch rail locking members.

16. In a railway switch lock, a rocker member having a vertical slot, a bracket 60 having a vertical slot, a block received in the slot of the rocker member, locking bars pivotally connected with the rocker member, and means engaging said block and disposed in the said slots for varying the throw of 65 the locking bars.

In testimony whereof I affix my signature.
JOSEPH R. DOOLEY.
